UNITED STATES PATENT OFFICE.

JAMES H. RAND, JR., OF TONAWANDA, AND LOUIS C. BROECKER, OF BUFFALO, NEW YORK, SAID BROECKER ASSIGNOR TO SAID RAND.

INDEX DEVICE.

Application filed November 9, 1923. Serial No. 673,739.

To all whom it may concern:

Be it known that we, JAMES H. RAND, Jr., and LOUIS C. BROECKER, citizens of the United States, residing at Tonawanda and 5 Buffalo, respectively, in the county of Erie and State of New York, have invented a new and useful Improvement in Index Devices, of which the following is a specification.

- 10 This invention relates to record or index card or card-holder trays or supports and more particularly to devices for maintaining cards or card-holders in proper position on the trays or supports.
- 15 Heretofore, card indexes have been provided comprising trays or supports on which are positioned a plurality of cards or card-holders, the card or card-holders being provided with flaps whereby the heads of adjacent cards or holders may be inserted therebeneath to maintain the cards or card-holders nested in overlapping arrangement with the edges of the cards projecting one beyond the other. The trays have further been 20 provided with side flanges or guide members beneath which tongues or the like on the cards or holders engage so that the cards or holders may be releasably connected to the tray or support. Follower blocks or 25 members have also been provided which are adapted to be engaged with a portion of the tray and to bear against one or more of the cards or holders with a view to holding the nested cards or holders in the tray in 30 proper position and preventing unintentional removal thereof. These latter devices as heretofore constructed have been relatively difficult to position and operate. Certain of these follower devices, having parts 35 for engaging lugs or teeth on the bottom of the tray and another part for bearing against the card or holder, depend upon the cards or holders for support in one direction, and if the cards or holders are not fully 40 compressed when the devices are put in position, there is not sufficient pressure upon the followers to maintain them in position, with the result that they may become disengaged from the trays. Again, these devices 45 as a rule have to be positioned and adjusted within the tray and it is often difficult and inconvenient to follow such procedure. Further, with the type employing a sliding follower block cooperating with lugs or other 50

projecting parts on the bottom of the tray 55 for maintaining the follower in position, the number of cards or holders which may be secured in the tray cannot be widely varied, as it is not practical to provide lugs or projecting parts beneath any portion of the tray 60 on which the cards or holders slide without liability of serious damage to the cards or holders.

The objects of the present invention are to provide a card or card-holder tray or the like having a follower or member which is held in position by a portion of the tray other than the bottom thereof; also to provide a card-follower or securing device which is readily extensible, whereby it may 65 be used to secure any desired number of cards in the tray, and also to provide a follower or securing device which may be readily actuated from the outside of the tray. Further objects are to provide improvements 70 in card-followers or securing devices in the other respects hereinafter set forth and claimed.

In the accompanying drawings:

Fig. 1 is a longitudinal section on line 80 1—1, Fig. 2, of a card or card-holder tray provided with a follower or member for maintaining the cards or holders in position in the tray, said follower being constructed in accordance with one embodiment of the 85 invention.

Fig. 2 is a plan view of the front portion of the tray, the holders being broken away to disclose the parts beneath.

Fig. 3 is a view similar to Fig. 1, with 90 the follower stem partly withdrawn through the front wall of the tray.

Fig. 4 is a section of the stem part of the follower, on line 4—4, Fig. 6.

Fig. 5 is an enlarged plan view of the 95 spacing or extensible stem portion of the follower with the channel member thereof detached.

Fig. 6 is an enlarged longitudinal section 100 of the stem portion of the follower.

Fig. 7 is a fragmentary plan view of a tray provided with a modified form of follower.

Figs. 8 and 9 are longitudinal sectional 105 views, on line 8—8, Fig. 7, showing the follower in operative and partly withdrawn positions, respectively.

Fig. 10 is a fragmentary plan view of the

follower shown in Fig. 7, partly in section to disclose the stem portion thereof.

Figs. 11 and 12 are transverse sections on line 11—11, Fig. 7, with the parts in 5 different positions to show the action of the stem-holding spring.

Fig. 13 is a transverse section on line 13—13, Fig. 10.

Fig. 14 is a fragmentary plan view of the 10 follower showing the stem portion released from the sliding plate.

Fig. 15 is a fragmentary plan view of a tray provided with another modified form of follower.

15 Figs. 16 and 17 are longitudinal sectional views, on line 16—16, Fig. 15, with the follower in closed and partly withdrawn positions, respectively.

Fig. 18 is a sectional plan view of the 20 adjustable follower stem.

Fig. 19 is a face view of the outer end thereof and a portion of the front wall of the tray.

Fig. 20 is a transverse section of the stem 25 on line 20—20, Fig. 18.

Figs. 21 and 22 are fragmentary plan views, partly in section, of the front part 30 of a tray provided with, and showing two different adjustments of, another modified form of follower.

Fig. 23 is a longitudinal section thereof on line 23—23, Fig. 21.

Figs. 24 and 25 are transverse sections 35 thereof on lines 24—24 and 25—25 respectively, Fig. 21.

Fig. 26 is a sectional plan view showing the released position of the adjustable stem of the follower.

Fig. 27 is a fragmentary transverse section 40 on line 27—27, Fig. 22.

The present invention, generally stated, comprises a tray or other supporting member for receiving a plurality of cards, card-holders or other record-members and a movable follower or device for engaging one of 45 said cards or other members, said follower or followers also engaging a portion of the tray or support outside of the portion of the tray normally occupied by the cards or other members when they are in position. This follower or holding member is preferably extensible so that it may be used to secure any desired number of cards or card-holders on the tray and preferably has 50 a part extending to the outside of the tray, whereby it may be actuated from without the tray for the purpose of disengaging it from the cards or record-members to permit their removal and for adjusting the follower 55 to change its length so that it may properly engage and retain a varying number of cards or record-members on the tray.

A designates a tray or other supporting device which receives a series or a plurality 60 of card holders B. As is a usual practice,

and as shown in the drawings, these card holders may be in nested, overlapping arrangement on the tray and the tray may be provided with side flanges C adapted to engage tongues D on the card-holders, which project beneath the flanges so that the cards are maintained in sliding engagement with the tray. The tray may be provided, if desired, with a fixed part or portion which provides a stop for one of the series of card-holders to limit the extent to which they may be moved in one direction longitudinally of the tray. For this purpose, in the device illustrated, there is shown a back stop E which engages the head of the rearmost holder of the series. This back stop E, as illustrated, may have an overhanging bead or portion F for the purpose of engaging the upper edge of the head of the rearmost card-holder to prevent the card-holders from being lifted out of the tray when the rearmost holder is in engagement with the back stop.

10 designates a movable card-follower or securing device. This device is preferably provided with a part for engaging one of the series of holders on the tray, such for example, as the sliding part or plate 11 shown in the drawings, and also a part for engaging a portion of the tray, whereby the device may be releasably maintained in position. As illustrated, the sliding plate 11 is preferably provided with ears or tongues T which engage beneath the side flanges of the tray and guide the plate in its sliding movements. For releasably maintaining the device in proper position, a spacing portion 12 is provided which is connected to the plate portion 11 and has a part preferably in engagement with the part of the tray 105 adjacent the front edge thereof. The spacing portion is preferably extensible so that the number of card-holders on the tray may be varied and the securing device still perform its function of effectively holding the card-holders on the tray. This extensible portion of the securing device may be of any desired form. For example, in Fig. 1, the plate member 11 is provided with a stem 14 having a spring-pressed stud 15. The portion bearing this stud is slidable in a channel 16 which has suitable recesses 17 into which the stud may engage. These recesses 17 are spaced apart longitudinally of the channel and the stem and channel with 115 the stud and recesses described, provide a member which is readily extensible for varying the distance between the plate member of the follower and the front of the tray. The channel member 16 is provided with a part or parts, as for example, the shoulders 18, for engaging a part of the tray. In the form shown, these shoulders 18 engage a portion of the front wall of the tray adjacent the opening 19 through which the ex- 120 125 130

tensional spacing member is slidable. The extensible member may be provided with a button or hand-pull 20 at the outside of the tray and has suitable means for causing the shoulders on the extensible member 12 to engage the wall of the tray. For this purpose, as illustrated in Fig. 1, a spring strip 21 may be provided which is adapted to bear upon a portion of the front of the tray and 5 to urge the shoulders on the channel into engagement with the front of the tray. The spring 21 is preferably so formed and positioned that its free end is enclosed in the button or hand pull. In order to release 10 the device, the button or hand pull may be pushed down against the action of the spring strip 21, whereupon the shoulders on the channel piece will disengage from the front of the tray and the extensible member 12 15 may then be pulled outwardly through the opening in the tray front. As illustrated in Figs. 3 to 6, the extensible member may be readily adjusted by pushing the button 20 downwardly and pulling the extensible member outwardly. The spring stud 15 may 20 then be readily lifted, the channel member 16 moved to any desired position relatively to the stem 14, and the stud inserted in another recess in the channel member. 25

30 The extensible portion of the follower may be constructed in different suitable forms, for example, in the modified form shown in Figs. 7-14, 11^a designates the plate or sliding member having guiding ears T' and the extensible part of the follower is made 35 in the form of a rack 22 having a plurality of teeth 23. This rack is slidable through an apertured portion 24 of the plate member and the teeth of the rack are caused to engage an edge of the apertured portion by 40 suitable means, such, for example, as the spring 25 on the plate member which bears against the straight side of the rack. This spring normally urges the rack to one side 45 so that its teeth will engage the edge of the apertured portion of the plate. The extensible portion or rack is provided with a suitable part for engaging a portion of the tray. For this purpose, in the form shown there 50 is provided a shoulder 26 on one side edge of the extensible part, which engages an edge of the front of the tray adjacent the aperture 27 through which the extensible part slides. 28 designates a button or finger piece whereby the follower of this form may 55 be actuated.

In Figs. 15 to 20, there is shown another modified form. In this form the sliding plate member 11^b, preferably having guide ears or tongues T², is provided with a screw-threaded stem 29. This screw-threaded stem cooperates with a handle portion 30 having an internal screw-thread 31. The handle portion 30 is slidable through an aperture 32 in the front of the tray and 60 has a part for engaging the tray front, whereby the follower may be held in position within the tray. In the form shown, this part has a shoulder 33 which is adapted when the follower is pushed into the tray 70 to engage behind the front wall of the tray. The stem is provided with a suitable button 34 at the outside of the tray so as to permit actuation of the follower from the outside of the tray. The handle 30 may be released by pushing inwardly and upwardly upon the button 34, whereupon the handle may be pulled outwardly through the front of the tray. The device is adjusted for 75 distance by pulling the handle 30 out to 80 clear the front wall of the tray, and then turning the handle portion upon the screw threaded stem to cause the plate member to project a greater or lesser distance into 85 the tray.

Still another modified form of follower device is shown in Figs. 21-27. The sliding plate member 11^c of this form is similar to the plate 11^a, Fig. 7, and is provided with guide ears T³ to engage under the flanges C 90 of the tray. The adjustable stem portion of this follower preferably includes a lock bar 40 having means adapted to adjustably engage an edge of the plate 11^c and means for engaging a fixed part on the tray, and 95 a handle portion 41 to which said lock bar 40 is pivoted, and which extends outwardly beyond the front edge of the tray through an aperture 42. The lock bar 40 is pivoted at its inner end 43 to the handle portion to 100 lie substantially parallel and coincident with said handle portion when in locking engagement with the follower plate. The two members are together slidably supported on the follower plate 11^c by depressed, oppositely directed lugs 44-44 and 45-45 which 105 engage opposite sides and the under face of the part 41. These lugs are preferably stamped out and depend from the follower plate and permits of relative longitudinal 110 movements between the plate and the adjustable stem. The adjustable stem preferably passes through an apertured part 46 on the plate 11^c and is provided on one edge of the bar 40 with a rack or series of teeth 47 115 adapted to normally engage an edge of the aperture to prevent unintentional movement of the follower. The bar 40 is further provided with a depressed lug or hook 48, adapted to engage a part on the handle part 41, for instance, the cut-out shoulder 49 which is so positioned that when the lug 48 is in engagement therewith the rack 47 is held against the edge of the apertured part 46 and relative endwise movement between 120 the plate and lock bar is prevented. The handle portion 41 is preferably of substantially the same width as the aperture 46 through which it extends and the overlapping lock bar 40 is reduced, or of less width 125 130

at this point, so that, by disengaging the lug 48 from the shoulder 49 the bar may be given a limited swinging movement on the pivot 43 sufficient to disengage the rack 5 teeth from the edge of the aperture, as shown in Fig. 26. The means for holding the device in engagement with the tray include a tongue or shoulder 50 extending upwardly and forwardly from the lock bar 40, 10 said tongue being held in engagement with an edge of the aperture 42 in the front wall of the tray by a spring strip 52 secured to the handle part 41 and engaging in the push button 53 which is secured to the front end 15 of the number 41. To disengage the device from the front of the tray for permitting its release from the cards or holders, the button 53 is depressed and moved inwardly to release the tongue 50 from the tray front, 20 whereupon the device may be pulled outwardly by keeping the spring strip 52 depressed until the tongue is free of the tray. In this position the lock bar is accessible and if it is desired to make an adjustment 25 for a different number of cards or holders the lock bar is moved upwardly and swung as shown in Fig. 26, so that the lug 48 is freed from the shoulder 49 and the teeth 47 are clear of the edge of the aperture 46. If 30 desired, the inward movement of the adjustable stem portion may be limited, as for instance by the shoulder 54 on the handle portion 41, which is adapted to engage a part on the follower plate, as for instance, the 35 apertured portion 46. This shoulder preferably coincides with the last tooth on the rack 47 thereby preventing the stem from being pushed in to an extent where the stem would be prevented from proper locking engagement with the follower plate.

In these devices described, the followers or plates having parts in engagement with the front wall of the tray and extending therethrough, are effectively maintained in 45 connection with the tray. They are not liable to fall out or become misplaced. The stems or extensible parts of the several devices may be of any desired length or any desired degree of extensibility so that the 50 followers may be used to maintain any desired number of the cards in place in the tray. The follower devices of this invention engaging the fixed front wall or other part of the tray and being connected thereto, do not depend upon the cards or holders 55 for maintaining their positions in the tray. The fixed stop adjacent the rear of the tray limits movement of the cards or holders longitudinally toward the rear of the tray 60 and the extensible followers which may be made of any desired length effectively secure the cards or holders against movement forward in the tray.

The handles of the movable follower or 65 securing devices projecting exteriorly at

the ends of the trays or receptacles may be used to move the trays or receptacles bodily as well as to actuate the follower devices.

We claim as our invention:

1. In a record-holding tray, the combination of a part providing a stop for engaging a portion of a series of record devices disposed in predetermined order flatwise on said tray to prevent movement of said series in one direction longitudinally of said tray, and an extensible member having a part releasably engaging a portion of said series for preventing movement of said series longitudinally of said tray in the other direction. 70

2. In a record-holding tray, the combination of a part providing a stop for engaging a portion of a series of record devices disposed in predetermined order flatwise on said tray to prevent movement of said series in one direction longitudinally of said tray, an extensible member having a part engaging a portion of said series, and a part extending adjacent an outer edge of said tray for releasably preventing movement of said first mentioned part and said series longitudinally of said tray in the other direction. 85 90

3. In a record-holding device having an outer side portion and parts for supporting a series of record members in predetermined arrangement flatwise on said device, the combination of a part on said device providing a stop for engaging a portion of said series of record members to prevent movement of said members in one direction longitudinally of said device and a cooperating member having a part for engaging a portion of said series for preventing movement of said series longitudinally of said device in another direction and an operating part releasably engaging said outer side of said device. 95 100 105

4. In a record-holding tray having a side portion and parts for supporting a series of record members in predetermined arrangement, flatwise on said tray, the combination of a part on said tray for engaging a portion of said series to limit movement of said series longitudinally of said tray in one direction, and a movable member having a part for engaging a portion of said series of record members to hold said series against longitudinal movement in the other direction, and an extensible part for releasably engaging a part of said tray, whereby a varied number of record members may be held against longitudinal movement on said tray. 115 120 125

5. In a record-holding container having a side portion and parts for supporting a series of record devices in predetermined flatwise nested arrangement in said container including parts on said container for preventing movement of said devices transversely of said container, the combination of 130

- a part on said container for engaging a portion of said series to limit movement of said series longitudinally of said container in one direction, and a movable member having a part for engaging a portion of said series of record devices to releasably hold said series against longitudinal movement in the opposite direction, and an extensible part for releasably engaging a part of said container whereby said movable member part may be held in different positions in said container. 75
6. In a record device, the combination with a plurality of spaced record-receiving devices having interlocking parts whereby the devices are nested in series in overlapping arrangement, of a container having parts for supporting said devices and a part for engaging one of said devices for limiting movement of said series lengthwise of said container in one direction, and an extensible member having a part for engaging one of said record devices and a part for releasably engaging a fixed part of said container for releasably holding said series of devices against movement lengthwise of said container in the other direction. 80
7. In a record device, the combination with a plurality of record-receiving devices having interlocking parts whereby the devices may be nested in series in overlapping arrangement, of a tray having parts for supporting said devices and a part for engaging one of said devices for limiting movement of said series lengthwise of said tray in one direction, and a member having a part for engaging one of said devices on said tray and a part releasably engaging a portion of said tray and operable from the exterior of said receptacle for releasably holding said series of devices against movement lengthwise of said tray in the opposite direction. 85
8. In a record device, the combination with a plurality of record-receiving devices having parts whereby the devices may be held in spaced overlapping arrangement, of a tray having parts for supporting said devices, side parts for engaging portions of said devices to maintain said devices against transverse movement on said tray, and a part for engaging one of said devices to limit shifting of said series longitudinally of said tray in one direction, and a securing member having a part engaging one of said devices, parts engaging the side parts of said tray, and a part extending to the exterior of said tray and releasably engaging a portion of said tray for releasably holding said devices from longitudinal movement on said tray in the other direction. 90
9. The combination with a plurality of record-receiving devices having interengaging parts whereby the devices may be nested in overlapping arrangement, of a tray having parts for supporting said devices and a wall with an aperture therein, and a securing device having a part provided with a portion for engaging one of said record-receiving devices for releasably holding said record-receiving devices against movement on said tray in one direction and a handle, said handle having a portion extending through the aperture in said tray wall whereby said securing device may be actuated from the outside of said tray. 95
10. In a record device, a tray having a portion for supporting record-displaying members in predetermined flatwise order substantially parallel with said supporting portion, and an end wall having an opening therein, a securing device having a part movable on said tray for engaging and holding said record-displaying members and a part extending through said end wall opening to the exterior of said tray whereby said securing device may be operated from the outside of said tray to disengage it from and release said record-displaying members. 100
11. In a record-holding receptacle having a portion for supporting a series of record devices in predetermined arrangement, the combination of a part providing a stop for engaging a portion of said series of record devices to limit movement of said devices relatively to said receptacle in one direction, and an extensible member having a part engaging a portion of said series of record devices for limiting movement of said series relatively to said receptacle in the opposite direction, said extensible member having a relatively fixed part, and a movable part having a series of selectively spaced engaging portions thereon, said relatively fixed part having a portion adapted to be engaged by said selectively spaced engaging portions and said movable part having a portion for engaging a part of said receptacle whereby the distance between the part of said extensible member engaging the record devices and the part of said receptacle engaged by said extensible member may be varied according to the size and number of record devices to be held on said receptacle. 105
12. In a movable stop for trays for supporting record-receiving devices, a pair of relatively movable members, one of said members having a part for engaging record-receiving devices on said tray and a part for engaging the other of said members, said other member having a plurality of selectively spaced parts movably mounted so as to be moved into or out of engagement with said first member engaging part and a part for engaging a portion of the receptacle, whereby the distance between said receptacle-engaging part and the record device engaging part may be varied. 110
13. In a movable stop for trays for supporting record-receiving devices, a pair of relatively movable members, one of said 115
- 120
- 125
- 130

- members having a part for engaging record-receiving devices on said tray and a part for engaging the other of said members, said other member comprising a handle portion adapted to extend from said first member to the outside of said tray, and a movable member on said handle having a plurality of selectively spaced parts for engaging the part on said first member, and a part 10 for engaging a portion of said tray, whereby said first member may be caused to project more or less into said tray.
14. In a record device, a receptacle having a portion for supporting record-displaying members in recumbent positions and an end wall, said end wall having an opening therein, an extensible securing device having a part movable in said receptacle for engaging and holding said record-displaying members and a part extending through said end wall opening to the exterior of said receptacle, whereby said securing device may be operated from the outside of said receptacle to disengage it from and release said record displaying members.
15. In a record device, the combination of a card-record receptacle adapted to support a plurality of record members in recumbent or horizontal positions, and a follower block 20 movable in said receptacle, said follower block having a portion extending through an end of said receptacle whereby it may be accessible and is adapted to be moved from the exterior of said receptacle.
16. The combination of a receptacle a plurality of spaced record cards in recumbent positions in said receptacle, a securing member having a part which engages the cards in said receptacle, a part extending outside of said receptacle and provided with a handle and parts releasably connecting said handle part to said receptacle, whereby said securing member may be moved relatively to said receptacle from the outside of said receptacle by manipulating said handle or the receptacle may be moved bodily by said handle without shifting said securing member relatively to the receptacle.
17. In a card index, a card-receptacle, a plurality of cards in recumbent positions therein, and a movable follower member for releasably holding said cards in position in said receptacle, said follower member having a part extending to the exterior of said receptacle whereby it may be actuated from the outside of said receptacle.

JAMES H. RAND, JR.
LOUIS C. BROECKER.
